AUTOMATIC BANJO MUTE.

Application filed August 2, 1926. Serial No. 126,408.

Our invention relates to muting devices for musical instruments in the nature of banjos and the like.

Since it is, at present, difficult to mute an instrument while playing, as it necessitates the placing of the mute on the bridge by the player who thus loses several bars of the music, one object of our invention is to provide an improved mute for dampening the vibrations of the diaphragm of a musical instrument, and also to provide such means that the player may operate the mute independently of his hands while the instrument is being played.

15 The secret of operation of the device which we have devised lies in the angle at which the instrument is disposed by the player, as will appear below, the muting mechanism being automatic and gravity-controlled.

20 A further object of our invention is the provision of a mute operating mechanism of relatively simple but durable and dependable construction, which is readily attached to or detached from the musical instrument, without requiring any change in the construction of the instrument, and which is entirely within the body of the instrument, thus eliminating from view all traces of the mechanism and in no way impairing the beauty or tone 25 of the instrument.

An important feature of our invention is the composition of the mute which we use. After long experiment with various metals and compositions, we have found that a mute 30 constructed of lead is best suited to absorb the musical vibrations and to give out softer and deeper tones. It is further to be noted that the lead mute, which, as will later be described in detail, slips into place in wedge-like fashion beneath the head and in registration with the bridge, the diaphragm being between the mute and the bridge, is self-lubricating due to the inherent slippery, oily character of the metal itself.

40 Further objects will become apparent from the following description and claims, taken in connection with the accompanying drawings in which:

Figure 1 is a view looking at the inside of the shell toward the head of a banjo equipped with the mute and gravity-controlled mechanism embodying our invention;

Fig. 2 is a substantially vertical sectional view of the circular body portion of a banjo

having attached thereto the mute and mechanism embodying my invention, and is taken on the line 2—2 of Fig. 1;

Fig. 3 is a substantially cross-sectional view, along the line 3—3 of Fig. 1, and in the direction of the arrows and discloses the mute and gravity-controlled mechanism embodying our invention secured on the stick of the banjo;

Fig. 4 is a perspective view of the muting member;

Fig. 5 is a detailed perspective view of the mute and gravity-controlled mechanism embodying our invention, the full-line showing the device in muting position and the dotted line showing the position of the weight and shaft when the device is not in muting position;

Fig. 6 is a perspective view looking at the device from a different angle, and

Fig. 7 is a detail perspective view of the block which carries the muting member and is carried by the gravity shaft.

Referring to Fig. 2, an ordinary banjo construction is shown with a rim 1 and a skin 2 which is stretched over a flesh hoop 3, said 50 hoop being retained in place in the usual manner by a tension ring 4. A bridge 5 is shown, supporting the strings 6 which extend from the tail-piece 7 to the neck which is indicated at 8 of Fig. 1.

Again referring to Fig. 2, a resonator is shown at 9, supported on the under-side of the rim by the clamp 10 which is fastened on the stick 17, said resonator being secured to said clamp by the screw 11. The resonator, 90 attached in this position, opposes the diaphragm or skin, but is spaced from the lower side of the rim by a substantial distance in order to provide an open resonating chamber.

The mechanism, to which the subject-matter of our invention more particularly relates, will now be described. In a general way, this mechanism comprises, as shown in Fig. 3, a muting member 12, the stem 22 of which is adjustably secured by the thumb screw 13 to a block or carrier 14, said block being secured to the shaft 15 which is, in turn, mounted in bearings 16, said bearings being secured upon the stick 17 by the clamp 18 with which the bearings are integrally formed. Said clamp 105 is secured to the stick by the thumb screws 23 and 24. A weight 19 is adjustably secured to the said shaft by the screw 20. The axis

of said shaft is disposed neither in the axis of the body, or shell, of the banjo, nor in the axis of the neck, but it is so disposed that any movement of the instrument, about the axis of either the body or the neck, will throw the weight off center, thus moving the device into muting position. It follows that the combination of a movement about the axis of the body and a movement about the axis of the neck will still more readily throw the weight off center.

The angle of the shaft may be changed to suit the player by means of the screw 21.

It will be noted, further, that the stem 22 of the muting member is flattened on one side so as to prevent said member from turning in the block.

This muting member is preferably made of lead, since experiment has shown that metal best adapted to be used with this device, for, not only is lead highly ductile, by which it is meant that it most readily absorbs musical vibrations, but also as it is self-lubricating due to its oily surface, it slides easily into wedge-like position in contact with the skin under the bridge. This self-lubricating quality of the lead is of importance, for, since it is necessary that the muting member be brought snugly under the bridge, the device so operates that when the weight falls off center, setting in motion the shaft and block attached thereto, the muting member is moved in an arcuate direction into contact with the skin, along the surface of which it moves, the pressure of said member against said skin increasing the farther the former is moved, until it is finally wedged up tightly under the bridge. Obviously, the oily character of the lead allows the muting member to slide along in contact with the skin without doing the latter any harm, and as it overcomes friction, without appreciably retarding the movement thereof while it is being forced into muting relation with the skin and bridge.

By "muting relation" is meant that position in which the muting member must be in relation to the skin and bridge to obtain the muted effect when the instrument is played. This position is obtained when the muting member is held in contact with the skin, and immediately under and registering with the bridge.

To describe the operation of our device more specifically, we shall now refer to Fig. 5. The dotted lines indicate the position of the weight 19' and shaft 15' when the instrument is held in normal position, the muting member 12 being, when the instrument is so held, disengaged and held away from the skin and bridge. Now, when the neck of the instrument, which is in the direction of *c*, is raised, or when the instrument is rotated in the direction of the arrow *d*, or when the instrument is given a slight tilt combining these

two movements, the weight 19' falls off center and moves, by the force of gravity, to the position shown in full lines at 19. As the weight moves to this new position, it causes the shaft 15' to rotate in the bearings 16, and this rotation, in turn, causes the block 14 to rotate in the direction of the arrow *e*. The muting member 12, being secured to the block 14, is moved, by the rotating movement of said block, in an arcuate direction until it comes in contact with the skin. The clamp 13 which secures the bearings 16 is so positioned upon the stick 17 that the muting member, after moving in the above mentioned arcuate direction, is slid along the skin, coming in ever tighter contact as the movement continues, and comes to rest, wedged in contact with the skin and in registration with the bridge, causing many of the vibrations coming through the bridge to be absorbed by the muting member, thus cutting down the vibrations emanating from the head of the instrument.

When the instrument is moved or tilted in directions the reverse of those above described, the weight 19 falls back into the dotted-line position, causing the shaft to rotate in a direction the reverse of the above described, which, in turn, causes the muting member to leave its wedged position and to break its contact with the skin, thus bringing it back to its disengaged position and allowing the vibrations to emanate forth from the head in their full volume.

In Fig. 7 it will be noted that the block 14, which is carried on the shaft 15, is slotted, as shown in 25, so that the said shaft may be easily and securely mounted therein against rotation by turning down the thumb screw 26.

It will thus be seen that our improved muting device may be quickly and conveniently attached to any instrument having a vibratory head, such, for instance, as a banjo, without changing any of the parts or mutilating the instrument, and without any part of the device being exposed to view.

It will also be readily seen that the gravity control of the muting member will permit of the instrument being muted by a slight rotation of the body, or a tilting of the same, which movements will in time be performed subconsciously by the player when it is desired to produce soft and muted tones.

While we have shown and described a preferred embodiment of our invention, it will be understood that the details of construction are capable of wide modification and variation, while still retaining the fundamental principles thereof. Hence, we reserve all such modifications, variations and mechanical equivalents as fall within the spirit and purview of the appended claims.

We claim:

1. In combination with a stringed musical

instrument having a bridge and a vibratory head, a gravity-controlled muting member acting directly on the vibratory head.

2. In combination with a stringed musical instrument having a bridge, a body portion and a vibratory head, a gravity-controlled muting member contained wholly within the body of the instrument.

3. In combination with a stringed musical instrument having a bridge and a vibratory head, a muting member, a gravity-controlled weight for moving said member in an arcuate direction to wedge the same into muting relation with respect to the said head and bridge, and means for securing the muting member and gravity-controlled weight within the body of the instrument.

4. In combination with a stringed musical instrument having a bridge and a vibratory head, an adjustable muting member, gravity-controlled means for moving said member in an arcuate direction to wedge the same into muting relation with respect to said head and bridge, and means for securing the muting member and gravity-controlled weight within the body of the instrument.

5. In combination with a stringed musical instrument having a bridge and a vibratory head, a muting member, adjustable gravity-controlled means for moving said member in an arcuate direction to wedge the same into muting relation with said head and bridge, and means for securing the muting member and gravity-controlled weight within the body of the instrument.

6. In combination with a stringed musical instrument having a bridge and a vibratory head, an adjustable muting member, adjustable gravity-controlled means for moving said member in an arcuate direction to wedge the same into muting relation with said head and bridge, and means for securing the muting member and gravity-controlled weight within the body of the instrument.

7. In combination with a stringed musical instrument having a bridge and a vibratory head, a muting member, gravity-controlled means for moving said member in an arcuate direction to wedge the same into muting relation with said bridge and head, and adjustable means for securing the muting member and gravity-controlled weight within the body of the instrument.

8. In combination with a stringed musical instrument having a bridge and a vibratory head, an adjustable muting member, gravity-controlled means for moving said member in an arcuate direction to wedge the same into muting relation with said bridge and head, and adjustable means for securing the muting member and gravity-controlled weight within the body of the instrument.

9. In combination with a stringed musical instrument having a bridge and a vibratory head, a muting member, adjustable gravity-

controlled means for moving said member in an arcuate direction to wedge the same into muting relation with said bridge and head, and adjustable means for securing the muting member and gravity-controlled weight within the body of the instrument.

10. In combination with a stringed musical instrument having a bridge and a vibratory head, a muting member adjustable with respect to the vibratory head, adjustable gravity-controlled means for moving said member in an arcuate direction to wedge the same into muting relation with said bridge and head, and adjustable means for securing the muting member and gravity-controlled means within the body of the instrument.

11. A muting device for stringed musical instruments which have a bridge and a vibratory head, comprising a muting member and gravity-controlled means for moving said member in an arcuate direction to wedge the same into muting relation with the said head and bridge.

12. A muting device for stringed musical instruments which have a bridge and a vibratory head, comprising a muting member, gravity-controlled means for moving said member in an arcuate direction to wedge the same into muting relation with the said head and bridge, and means for securing the device within the body of the instrument.

13. A muting device for stringed musical instruments which have a bridge and a vibratory head, comprising a muting member and means acting automatically upon the shifting of the position of the instrument to move the said member into registration with the said bridge and into contact with said head for muting the vibrations thereof.

14. A muting device for stringed musical instruments which have a bridge and a vibratory head, comprising a muting member, clamping means, and means acting automatically upon the shifting of the position of the instrument to move said member into contact with said head and into registration with said bridge.

15. A muting device for stringed musical instruments which have a bridge and a vibratory head, comprising an adjustable muting member, clamping means, and means acting automatically upon the shifting of the position of the instrument to move said member into contact with said head and into registration with said bridge.

16. A muting device for stringed musical instruments which have a bridge and a vibratory head, comprising a muting member, clamping means, and gravity-controlled means for moving said member into registration with said bridge and into contact with said head for muting the vibrations thereof.

17. A muting device for stringed musical instruments which have a bridge and a vibratory head, comprising an adjustable muting

member, a gravity-controlled adjustable means serving to bring said member into muting relation with said bridge and head, and means for adjustably clamping the mute to the instrument.

18. A muting device for stringed musical instruments which have a bridge and a vibratory head, comprising an adjustable muting member, a gravity-controlled adjustable weight for moving said member into registration with said bridge and into contact with said head and means for adjustably clamping the mute to the stick of the instrument in such manner that the device is entirely contained within the body of the instrument.

19. A muting device for stringed musical instruments which have a bridge and a vibratory head, having in combination, a muting member, clamping means, and gravity-controlled means for operating said mute, said muting member composed of material suited to absorb musical vibrations and means for moving said member into register with said

bridge and into contact with said head; said clamping means serving to secure the device within the body of the instrument, and said gravity-controlled means comprising an adjustable weight on a shaft connected to the said member, said shaft being so positioned that the weight will fall off center on certain movements of said instrument.

20. A muting device for stringed musical instruments which have a bridge and a vibratory head, comprising a member composed of a ductile material capable of absorbing musical vibrations, and a gravity-controlled means for bringing said member into registration with the said bridge and into contact with said head for muting the vibrations thereof.

In witness whereof, we have hereunto subscribed our names.

W. JULIAN DAVIDSON.
